W. W. LAMB.

TRACK CLEANING MACHINE.

APPLICATION FILED JAN. 5, 1910. RENEWED SEPT. 23, 1912.

1,061,549.

Patented May 13, 1913.

UNITED STATES PATENT OFFICE.

WILBERT W. LAMB, OF ALHAMBRA, CALIFORNIA, ASSIGNOR TO THE LAMB RAILWAY SERVICE COMPANY, OF CINCINNATI, OHIO, A CORPORATION OF OHIO.

TRACK-CLEANING MACHINE.

1,061,549.

Specification of Letters Patent.

Patented May 13, 1913.

Application filed January 5, 1910, Serial No. 536,468. Renewed September 23, 1912. Serial No. 721,924.

To all whom it may concern:

Be it known that I, WILBERT W. LAMB, a citizen of the United States, residing in the city of Alhambra, county of Los Angeles, 5 and State of California, have invented new and useful Improvements in Track-Cleaning Machines, of which the following is a specification.

My invention relates primarily to a machine for melting the snow from railroad tracks or streets or roads, although its use is not restricted to that purpose, and the object thereof is to produce a machine having great heat producing capacity which 15 can be operated by liquid hydro-carbon fuel in the coldest of weather.

I have illustrated my device as applied to a railroad car, but it can be mounted upon other forms of running gear to use upon 20 streets, and other places where the services of such a machine may be required.

In the drawings accompanying this application and forming a part thereof: Figure 1 is a plan of my machine. Fig. 2 is a side 25 elevation partly in section and partly broken away of my machine. Fig. 3 is a top plan of the lower half of one of the burner cylinders. Fig. 4 is a rear end view of a burner cylinder. Fig. 5 is a section on the 30 line 5—5 of Fig. 3. Figs. 6 and 7 are detail views of the generating tubes of the vaporizing coil.

In the drawings 10 may be an ordinary flat railroad car upon the rear end of which 35 is secured the liquid hydro-carbon fuel tank 11 which is supplied with compressed air at the top thereof through a hose 12, which is connected up to the ordinary air pipes not shown, or to any other suitable compressed air supply.

13 is a liquid hydro-carbon fuel supply pipe which leads from near the bottom of the fuel tank and connects to the generating coil 14, which is located in the lower half 45 of the burner cylinder, the size of this pipe depending upon the capacity of the machine.

In the drawings I have shown two burner cylinders as I consider that to be an 50 appropriate number for a machine for use in melting snow upon a railway track. When more than one burner cylinder is used pipe 13 branches near the cylinders and a branch runs to each vaporizing coil 55 of which there is one in each burner cyl-

inder. The vaporizing coils are formed of a plurality of generating tubes 14^a which extend from near one end of the burner cylinder to near the other end of the burner cylinder and are connected by pipe fittings 60 consisting of T's 16 and nipples 16^a connecting the T's. At the other end return bends 17 connect the tubes. One of the outlets of the T is closed by a plug 18 so that access can be had to the interior of the generating 65 tube for the insertion and removal of the vaporizing web 19 and for cleaning the same. This vaporizing web is preferably in the form of a cross, as best shown in Fig. 7, and practically divides the tube into four 70 channels 20. At suitable distances these channels are connected by kerfs or grooves 21 cut in the outer edges of the web, as best shown in Fig. 6. The other side of the vaporizing coil is connected by suitable 75 fittings to the needle valve 22 which controls the discharge of vapor into the burner cylinder 15. The rear end of the burner cylinder is partially closed leaving a central port 23 into which the vapor is discharged 80 from the needle valve, thereby entraining a certain amount of air into the burner cylinder. When the vapor is lighted it burns with a strong flame which heats up the interior of the burner cylinder, thereby 85 vaporizing the liquid fuel passing through the vaporizing coil.

The burner cylinder is preferably provided on the lower side thereof with rows of perforations 24 through which air is drawn 90 to aid the combustion of the vapor which is to become heated and to be forced out through the outer end of the burner cylinder against the snow and ice on the track, thereby melting the same. It will be understood 95 that suitable provision will be made to heat the vaporizing coil before the machine starts to work, such as by a fire either in or under the burner cylinder. The burner cylinders are carried by the burner frame 25 which is 100 pivotally connected at 26 to the derrick 27. The derrick is mounted on wheels 28, which wheels run upon a track 29 formed of U-shaped iron secured upon the platform of the car, the tread of the wheels running in 105 the channel 30 of the track. In the bottom of the derrick frame is mounted an air cylinder 31 which is rigidly secured to the derrick frame. Extending longitudinally through the cylinder and projecting at each

end thereof is a piston stem 32 which is secured to bearings 33 mounted upon the platform of the car. This piston stem carries a piston not shown, within the cylinder which has a working fit therein. The opposite ends of the air cylinder are connected by pipe 34 in which is mounted a four way valve 35 by means of which either end of the piston can be thrown to pressure, while at the same time the opposite end is thrown to exhaust. This valve is connected by pipe 36, having a flexible section 36a therein, to the air supply by means of which the device is operated. A branch pipe 37 leads from pipe 36 near valve 35 to the front end of a second air cylinder 38 which may be termed the height regulating air cylinder. Pipe 37 is provided with a three way valve 39 by means of which the cylinder is thrown to pressure or exhaust as desired. This cylinder carries a piston not shown, which is provided with a piston stem 40, which is connected by a flexible cable 41 with rods 42 which are secured to the front end of the burner frame. Cable 41 runs over a sheave 43 mounted on the derrick frame. The burner frame also carries rods 44 having eyes 45 through which pass chains 46. One end of each chain 46 carries a hook 47 by means of which the length of the chain can be regulated. The other end of the chain is secured to the derrick. By means of these last rods and chains the burner frame is secured at its adjusted height, the adjustment being obtained by means of cylinder 38 and connected mechanism. By means of cylinder 38 the burner frame can be carried to the horizontal position in which position it is adapted to be run rearwardly upon the car. Air can then be admitted into the inner end of cylinder 31 when the derrick carrying the burner frame will be caused to travel rearwardly on the car, in which position it is ready for transportation from one point to another. By admitting air into the upper end of cylinder 41, the derrick is run to the position shown in the drawings thereby carrying the burner frame projecting beyond the car. Its height is then adjusted by means of cylinder 38 and it is then secured in the adjusted position by means of the rods and chains, after which the coils are heated and the fire is lighted whereupon the machine is ready for use.

It will be observed that the vaporizing coil is protected by the burner cylinder from any drafts of wind or from any cold air, and that the fire burns within the burner cylinder near the outer end, thereby always keeping the vaporizing coil in a heated condition. I prefer to use a high air pressure, say about 150 pounds upon the fuel in the fuel tank, thereby forcing the vapor into the burner cylinder with great power, which causes the air to be drawn into the burner cylinder and

to be forced out of the same in a highly heated condition upon the snow and ice on the track just in front of the burner cylinders. By this construction I have provided a highly efficient machine which can be operated in all kinds of weather as the generating coil is fully protected from the weather.

It will be understood that a portion of pipe 13 will be made flexible so as to permit of the movement of the derrick to and fro on the platform of the car. Within the fuel tank, pipe 13 is provided with a self closing valve 48 and a strainer 49. The air supply pipe is also provided with a self closing valve. These self closing valves are adapted to be locked open when the machine is in operation, and the locking means are subject to the control of the operator so that in case of accidents, or when the machine is not in operation the valves may be closed. In my application 534,981, filed December 27th, 1909, I have shown a machine, which by a slight modification could be used as above set forth.

Having described my invention what I claim is:

1. The combination of a car platform and a derrick mounted thereon, with means to move said derrick longitudinally upon the platform; a burner frame carried by said derrick; a burner cylinder mounted upon said burner frame, said burner cylinder being partially closed at the rear end; a vaporizing coil within said burner cylinder, said vaporizing coil comprising a plurality of connected tubes extending longitudinally of the cylinder; vaporizing webs within said generating tubes; a needle valve adapted to discharge vapor into the rear end of said burner cylinder; a connection from said needle valve to said vaporizing coil; and means to supply liquid hydro-carbon fuel to said coil under pressure.

2. In a device of the character described herein, a running gear; a platform mounted upon said running gear; a derrick mounted upon said platform; means secured to said platform and to said derrick to move the derrick longitudinally upon said platform; a burner frame pivotally mounted upon said derrick; means secured to said burner frame and derrick adapted to adjust the height of the burner frame; a burner cylinder mounted upon said burner frame; said burner cylinder having a port in its rear end; a vaporizing coil within said burner cylinder, said vaporizing coil comprising a plurality of connected tubes extending longitudinally of the cylinder; vaporizing webs within said generating tubes; a needle valve adapted to discharge vapor into the port in the rear end of said burner cylinder; a connection from said needle valve to said vaporizing coil; and means to supply liquid hydro-carbon fuel to said coil under pressure.

3. In a device of the character described herein, a running gear; a platform mounted thereon; a derrick mounted on said platform; pneumatic means connected to said platform and to said derrick adapted to move the derrick frame longitudinally upon the platform; a burner frame pivotally secured to said derrick; means to adjust the elevation of said burner frame; a burner cylinder mounted on said burner frame; said burner cylinder being partially closed at the rear end; a vaporizing coil within said burner cylinder; said vaporizing coil comprising a plurality of connected tubes extending longitudinally of the cylinder; vaporizing webs within said generating tubes; a needle valve adapted to discharge vapor into the rear end of said burner cylinder; a connection from said needle valve to said vaporizing coil; and means to supply liquid hydro-carbon fuel to said coil under pressure.

4. In a device of the character described herein a burner cylinder, said cylinder be-

ing partially closed at the rear end; open 25 at the front end, and having longitudinal rows of perforations in the side walls thereof; a vaporizing coil within said cylinder, said vaporizing coil comprising a plurality of connected tubes extending longitudinally 30 of the said cylinder; vaporizing webs within said generating tubes; a needle valve to discharge vapor into the rear end of said burner cylinder, said needle valve being exterior the cylinder and adapted to discharge 35 vapor through the rear opening of the cylinder; a connection from said needle valve to said vaporizing coil in combination with means to transport said burner cylinder and means to supply liquid hydro-carbon fuel to 40 said coil under pressure.

In witness that I claim the foregoing I have hereunto subscribed my name this 30th day of December, 1909.

WILBERT W. LAMB.
